UNITED STATES PATENT OFFICE

MARCELLO CENTORRINO, OF NEW YORK, N. Y.

CIRCUIT BREAKER

Application filed January 6, 1928, Serial No. 244,895. Renewed July 15, 1930.

This invention relates to code teaching devices and more particularly to a circuit closing means therefor.

An object of the invention is to provide a circuit closer which is simple in construction and efficient in operation.

Another object of the invention is to provide a circuit closer which can be operated by a perforated tape.

10 A further object of the invention is to provide a circuit closer of such shape and construction that the tape will be subjected to a minimum amount of wear and the danger of tearing will be eliminated.

15 A still further object of the invention is to provide means for feeding the tape in a forward direction.

20 A still further object of the invention is to provide means for lifting and holding the circuit closer and the forward feeding means out of contact with the tape to permit the tape to be moved in a rearward direction.

25 A still further object of the invention is to provide easily operated means for accurately adjusting the gap in the circuit closer.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing 35 from the spirit of the invention.

In the accompanying drawing, forming a part of this specification, and in which like numerals are employed to designate like parts throughout the same:

40 Figure 1 is a vertical longitudinal section of the present invention,

Figure 2 is a vertical cross-section on the line 2-2 of Figure 1,

45 Figure 3 is a horizontal section on the line 3-3 of Figure 1,

Figure 4 is an enlarged detail view of the anti-friction bearings for supporting the circuit closing lever,

50 Figure 5 is an enlarged detail view of one end of the circuit closing lever and the tape

support showing the perforated tape passing therebetween, and,

Figure 6 is a similar view on the line 6-6 of Figure 5.

In the drawing, wherein for the purpose 55 of illustration is shown a preferred embodiment of my invention, the numeral 1 designates a housing wherein the various elements of the device are assembled.

A supporting plate 2 is secured in the 60 housing 1 and carries on its under side a tape guide 3. At one end the support is provided with depending lugs 4 which receive securing elements 5 of a tape support 6.

A tape 7 having perforations 8 in the form 65 of code signals is used and for the purpose of guiding said tape a notch 9 is cut in the tape support 6. Guides 10 and 11 are further provided to carry the tape 7 out of the housing 1.

A fixed cylindrical feeding roller 12 has its 70 trunnions 13 mounted for rotation in the housing 1, one of said trunnions carrying a pinion 14 for engagement with any suitable driving means such as a gear-wheel 15 connected with a source of power, not shown.

Above the fixed cylindrical feeding roller is a spring pressed roller 16 normally urged 75 toward the fixed roller by springs 17 secured to the housing 1 and exerting pressure 80 against trunnions 18 through slides 19 which rotatably receive the trunnions 18 and are held in right line movement by guides 20.

Upright lugs 21 are formed on the supporting plate 2 and carry adjustable anti-friction bearings 22 which receive the pointed ends 23 of trunnions 24 secured to a circuit closing lever 25 as clearly shown in Figure 4 of the drawing.

The circuit closing lever 25 has one end 26 90 bent at a right angle and disposed directly above the tape support 6 and is adapted to bear downwardly against the perforated tape 7 and receive motion therefrom as the said tape moves forwardly between the end 26 of the lever 25 and the tape support 6.

The end 26 of the contact lever 25 is shaped as shown in the drawing so as to pass over the tape 7 without injury thereto as hereinbefore stated.

An upturned end 27 is formed on the circuit closing lever 25 opposite the end 26 and is provided with a contact point 28 to be hereinafter more fully explained. The trunnions 24 of the lever 25 are located near the end 26 thereof so that the movement of the end 27 will be greatly increased as is obvious.

A vertical support 29 rises from the supporting plate 2 and carries a block of insulating material 30. The vertical support 29 carries a guide 31 which receives a contact screw 32. The guide 31 is insulated from the vertical support 29 and serves to carry an electrical current from the screw 32 to a conductor as will soon be brought out.

A U-shaped bearing plate 33 is mounted on the block of insulation 30 and receives the shaft 34 of a worm 35 which meshes with a worm-wheel 36 on the contact screw 32 to regulate the gap between the contact point 28 on the end 27 of the circuit-closing lever 25 and a contact point 37 on the contact screw 32. The shaft 34 is provided with a finger engaging piece 38 outwardly of the housing 1 whereby adjustment of the contact points 28 and 37 is secured. This adjustment is very slight and it has been found in practice that the worm 35 and the worm-wheel 36 remain in engagement throughout the entire range of movement.

In order to hold the end 26 of the circuit closing lever 25 in contact with the perforated tape at all times a spring 39 is secured to the lever 25 and to a tension regulating screw 40 threaded in the block of insulation 30.

After the perforated tape 7 has passed through the device and the user wishes to repeat the lesson a thumb-screw 41 is rotated. The thumb-screw 41 is screw threaded in the end of the housing 1 adjacent to the feeding rollers 12 and 16 and bears against a plate 42 secured to a rock shaft 43. Levers 44 and 45 are secured to the rock shaft 43 and extend under the trunnions 18 of the spring-pressed roller 16. The lever 45 is longer than the lever 44 and is extended backwardly and at a right angle as shown at 46 under the circuit closing lever 25.

Any suitable form of telegraphic sounder and battery not shown may be connected to the present invention and the current led therefrom to the device as will now be described.

The circuit includes the conductor 47, the bearing 22, the trunnion 24, the circuit-closing lever 25, the contact point 28, the contact point 37, the contact screw 32, the guide 31 and the conductor 48.

The operation of the device is as follows: The perforated tape 7 is threaded into the guide 3 and over the tape support 6, between the feeding rollers 12 and 16 and out through the guide 10. The gap between the contact points 28 and 37 is adjusted by means of the

finger piece 38 on the shaft 34 of the worm 35 and the device is ready for use.

When the user wishes to rewind the tape 7 he operates the thumb-screw 41 which bears against the plate 42 and rocks the rock shaft 43 carrying with it the levers 44 and 45 thus raising the feed roller 16 and the end 26 of the lever 25 off of the tape and holding it in elevated position until the tape is reversed a desired distance.

Having thus described my invention, I claim:

1. A device of the class described including a horizontal main support, upright lugs on said support receiving anti-friction bearings, a circuit closing lever having anti-friction trunnions mounted in said bearings, a cylindrical tape support carried by the main support and located below the forward end of the circuit closing lever, said cylindrical tape support having a groove for guiding the tape toward the said end of the circuit closing lever, said forward end of the lever being rounded to reduce friction and wear on the perforated tape, an adjusting spring connected to the lever at a point between its pivot and the opposite end of the lever for maintaining the rounded end in constant engagement with the tape and tape support, an electrical contact at the said opposite end of the lever, a stationary contact carried by the main support cooperating with the first mentioned contact, a forward feeding mechanism for the tape comprising a fixed motor actuated roller and a spring pressed roller normally in engagement therewith, means for disengaging the circuit closing lever and spring pressed roller out of contact with the tape to permit a reverse movement thereof, said means comprising a rock shaft, a plate on the rock shaft, a thumb screw engaging the plate to move the rock shaft on its axis, a pair of levers attached to the rock shaft and engaging the movable roller, one of said levers having an angular extension for engaging the forward end of the circuit closing lever whereby both of said levers will hold the movable roller and circuit closing lever out of engagement with the tape.

2. A device for teaching telegraphy including a transmitting lever actuated by a thin tape bearing perforations corresponding to characters of a telegraphic code, said lever having anti-friction trunnions mounted in anti-friction bearings, one end of said lever being adapted to close or open an electric circuit when the lever is actuated by the tape.

3. A device of the class described including a transmitting lever adapted to be actuated by tapes of various thickness, said tapes bearing indications corresponding to characters of a telegraphic code, said lever having anti-friction trunnions mounted in anti-friction bearings, one end of said lever having contact means associated therewith to close or

open an electric circuit when said lever is actuated by a tape, said means of contact being adjustable to permit the lever to utilize a desired amount of the thickness of the tape to operate said lever.

4. A device of the class described including a transmitting lever adapted to be actuated directly by tapes of various thickness bearing indications corresponding to characters of a telegraphic code, said lever having anti-friction trunnions mounted in anti-friction bearings, an electric contact cooperating with one end of the lever permits the closing or opening of an electric circuit when the lever is actuated by a tape.

In testimony whereof I affix my signature.
MARCELLO CENTORRINO.
